(57) **CLAIM**

The ornamental design for a combined ceiling fan motor housing and light fixture unit, as shown and described.

DESCRIPTION

FIG. 1 is a front elevational view of a combined ceiling fan motor housing and light fixture unit showing my new design, the rear elevational view being a mirror image thereof; FIG. 2 is a side view, taken for the left side of FIG. 1, the right side view being a mirror image thereof; FIG. 3 is a top plan view thereof; and, FIG. 4 is a bottom plan view thereof.

The broken line showing of environmental structure in FIGS. 1-4 is for illustrative purposes only and forms no part of the claimed design.
